UNITED STATES PATENT OFFICE.

HENRY A. MAURER, OF NEW YORK, N. Y.

DESIGN FOR A HOLLOW TILE.

SPECIFICATION forming part of Design No. 26,759, dated March 16, 1897.

Application filed December 1, 1896. Serial No. 614,135. Term of patent 14 years.

To all whom it may concern

Be it known that I, HENRY A. MAURER, a citizen of the United States, residing in the city, county, and State of New York, have invented and produced a new, useful, and original Design for Hollow Tiles, of which the following is a specification, reference being had to the accompanying drawings, forming part hereof, in which—

10 Figure 1 is a perspective view of my design. Fig. 2 is an end view, and Fig. 3 a side view thereof.

15 The leading feature of my design consists in a wedge-shaped hollow tile, the sides of said tile and its interior spaces or openings being formed by webs or partition-walls having substantially a double-X (XX) appearance in end view.

20 *a* is the top of the tile, longer at both ends than the bottom *b*, thus making the tile wedge-shaped in side view, as shown particularly in Fig. 3, the ends *c* thereof being flaring or downwardly tapering. A central longitudinal diamond-shaped space or opening *d* extends through the tile, and above and below

25 said opening at either side thereof are the oppositely-arranged triangular openings *e*. The said openings or spaces *d* and *e* are separated by the angularly-disposed webs or partition-walls *f*, the opposite outer sides of which 30 form the sides of the tile, which are therefore deeply indented, converging from the top and bottom inwardly to about the central horizontal line of said sides. The general effect in end view is that of a top and a bottom connected by webs or partition-walls of substantially a double-X (XX) appearance, as particularly illustrated in Figs. 1 and 2, said webs or partition-walls tapering inwardly or downwardly from the top to the bottom. 35 40

What I claim is—

The design for a hollow tile, substantially as herein shown and described.

Signed at the city, county, and State of New York this 19th day of November, 1896.

HENRY A. MAURER.
